UNITED STATES PATENT OFFICE.

LEONARD A. YOUNG, OF DETROIT, MICHIGAN.

SPRING CONSTRUCTION.

1,146,836.

Specification of Letters Patent. Patented July 20, 1915.

Application filed September 21, 1914. Serial No. 862,677.

To all whom it may concern:

Be it known that I, LEONARD A. YOUNG, a citizen of the United States of America, residing at Detroit, in the county of Wayne 5 and State of Michigan, have invented certain new and useful Improvements in Spring Construction, of which the following is a specification, reference being had therein to the accompanying drawings.

10 In the formation of upholstered seats for vehicles it is at times desirable to produce a particular contour, as for example, a swelling in the seat back to correspond to the curve of the back of the user. This is usually attempted by distribution of the upholstery material which is unsatisfactory as it either works out of place or mats down.

15 This invention relates to a form spring for upholstery seat construction whereby any contour that is desired is readily obtained and whereby applied upholstery maintains its position.

20 The invention consists in the matters hereinafter set forth and more particularly 25 pointed out in the appended claims.

In the drawings, Figure 1 is a view of one arrangement of a form spring that embodies features of the invention; Fig. 2 is a view in detail showing preferred details in 30 certain spring constructions; Fig. 3 is a view in detail with parts broken away showing a modification of the invention; Fig. 4 is a view in detail showing one means of securing a forming member; Fig. 5 is a view 35 in detail of a slightly different modification; Fig. 6 is a view of a further modified form; Fig. 7 is a view in detail showing the combination of the form strip with an auxiliary arch spring; and Fig. 8 is a view showing 40 another modification of the reinforcing forming member.

As herein shown a spring band 1 of suitable material is bent at its upper or lower end to form a rolled edge and is also 45 turned at the other end for support on the top and bottom or front and back members of a back or seat frame. The length of the strip is such that it takes the usual elliptical curve to arch over any body springs or like 50 construction that is used. A form member 3

of desired length is bent to give the proper set or curve desired, and is provided with flanges 4 which grip over the margin of the band 1 and impart the desired contour to it for the length of the form. Preferably 55 the members 3 are disposed in pairs as indicated in Fig. 6 that are arranged opposite each other and are held by suitable means as by slips 5.

The end portions of the band 1 are arranged to be secured to the seat frame in such manner as to prevent their being so fixed at any one point that they tend to sharply bend and become crystallized. One such means of holding them is shown in Fig. 60 1 in which the lower end portion 6 is thrust through a slot in the body of a U-shaped member 7 which is in turn clamped between the U-shaped flanges 8 of frame members 65 for carrying the body springs 9. The upper rounded portion 10 of the strip is secured to an off-set portion or upper margin of the frame by passage through an upper slotted bar 11 and a lower slotted bar 12. Or the construction shown in Fig. 3 may be used 70 75 where flat strips 13 and 14 have tongues 15 or ears 16 gripping the band. This not only imparts a permanent formation to the end portions of the strip, but holds them in such a manner that they have slight longitudinal play in the supports and therefore do not tend to crystallize and snap off as if held without chance for movement.

Various forms of the forming members may be used. As shown in Fig. 4 it may 80 consist of a strip 17 with inturned edges 18 in which case the other holding members 5 are omitted. Or there may be a pair of crimped wire members 19 applied with the flat oppositely disposed portions spread to 85 90 embrace the margin of the strip alternately. In such instance clips 20 hold the forming members in place. As shown in Fig. 6 these forming members may be applied at more than one place and in such instance a body 95 spring 21 is preferably used opposite the unreinforced portion of the band 1 so as to operate as an auxiliary spring when the form spring becomes partially depressed.

In the modification shown in Fig. 5, 100

where the spring and band is replaced by a pair of body wire springs in spaced relation, stiffening rods 27 are appropriately clipped to these as indicated.

- 5 In the modification shown in Fig. 7, forming means whereby a portion of the spring band is given a substantially permanent contour, may consist of a reinforcing spring a portion of whose length is securely clipped 10 to the spring band. As illustrated, the reinforcing spring may be an auxiliary arch 22, a portion of which is secured by suitable clips 23 against the inner face of the band 1 at that portion which it is desired to render 15 comparatively rigid and permanent in contour. Or the end portions 24 of the band 1 itself (Fig. 8) may be extended back from the supporting members 25 and securely fastened against the under face of the band 20 by cross strips 26. The latter as well as the corresponding parts shown in Fig. 6 are arranged to be moved up and down on the band to produce the desired result at the proper point.
- 25 It is understood that while the form and method of securing the ends of the band are preferably as herein illustrated, the band may be otherwise suitably counted as desired in a back frame or seat frame in such 30 a manner as to give the desired rounded edge and the cross sectional contour. The forming member may be applied on the band at the place desired and there secured by pinching down the ends of the flanges, or 35 otherwise fastening the parts in place.

Of course the form spring may be used in combination with a row of springs mounted on suitable strip members as indicated in Fig. 1 and enough of these sets may be supplied to complete a back or seat. Whatever 40 construction is used, the result when the upholstery is applied is a spring construction that presents the desired conformation and retains applied upholstery in the desired 45 shape. Because of the ability of the person assembling the spring to move the forming member up or down the band or form spring, it is possible to arrange the parts of a curved tonneau back or the like with the 50 exact curvature desired.

Obviously, changes in the details of construction may be made without departing from the spirit of my invention and I do not care to limit myself to any particular 55 form or arrangement of parts.

What I claim is:—

1. A form spring comprising a resilient band adapted to be secured near its extremities to the supporting means of a spring 60 structure, and means longitudinally adjustable thereon adapted to impart a predetermined permanent contour to the band for a portion of the length of the latter.

2. A form spring comprising a resilient

band having curved extremities by which it 65 is secured to a spring seat structure to arch thereover, and means adjustably mounted on the band and adapted to impart a permanent contour longitudinally of the band to a portion of the length of the latter. 70

3. A form spring comprising a resilient band adapted to be supported in arched relation over a spring seat structure, and forming means longitudinally adjustable on the band and having a permanent contour 75 to which it confines a portion of the band to which it is applied.

4. A form spring comprising a band of uniformly resilient material adapted to be supported near its extremities in arched relation to and over the body springs of a seat structure and forming means having a permanent predetermined longitudinal contour and adjustably engaging the band for a portion 80 of its length whereby the engaged portion is bent to conform to said contour. 85

5. In a spring seat structure, a form spring secured near its inbent extremities to the spring supporting members to arch over body springs and forming means adjustably 90 mounted on the band for maintaining a predetermined contour in the engaged portion of the band, the extremities of the band having limited longitudinal play at the 95 point of connection to the spring and supporting means.

6. A form spring comprising a resilient band adapted to be secured as an arch spanning the body springs of a seat structure, and a forming member of predetermined 100 longitudinal contour adapted to grip a marginal portion of the band and to hold that part of the band to which it is applied to the desired contour.

7. A form spring comprising a resilient band adapted to be bent into substantially regular arch between its ends, and a forming member having oppositely disposed flanged portions adapted to grip a marginal portion 110 of the band between them and confine the band for the length of the member to the desired contour.

8. A form spring comprising a resilient band adapted to be bent into substantially regular arch between its ends, a forming member having oppositely disposed flanged portions adapted to grip a marginal portion of the band between them and confine the band for the length of the member to the desired contour, and means for retaining the forming member in adjusted position. 115 120

9. A form spring comprising a resilient band adapted to be supported as an arch over the body springs of a seat structure, and means longitudinally adjustable on the band adapted to locally deform the band from the natural arch thereof for a portion 125 of the length.

10. The combination with a spring band bent to form an arch for a seat structure, of means adjustably secured to a portion of the band between its ends and adapted to confine a portion of the band to a predetermined contour, yieldingly supporting the confined portion of the band.
- 5

In testimony whereof I affix my signature in presence of two witnesses.

LEONARD A. YOUNG.
